UNITED STATES PATENT OFFICE.

FRANK CARTLIDGE, OF TERRE HAUTE, INDIANA.

CUTTER-HEAD.

1,074,834.

Specification of Letters Patent.

Patented Oct. 7, 1913.

Application filed August 19, 1911. Serial No. 643,421.

To all whom it may concern:

Be it known that I, FRANK CARTLIDGE, a citizen of the United States, residing at Terre Haute, in the county of Vigo and State of Indiana, have invented a new and useful Cutter-Head, of which the following is a specification.

There is one type of mining machine commonly in use in which the cutting is accomplished by means of cutters carried by the links of an endless chain which is carried, generally in a horizontal plane, at and across the forward end of a cutter head by means of which the cutting chain is carried bodily transversely into the breast of coal while it is at the same time being driven longitudinally. In such a structure the chain is supported, in the forward end of the cutter head, by means of idlers, over which it is drawn, and between the idlers is supported by wearing strips or members which resist lateral displacement of the chain. In such a cutter head, difficulty has been heretofore experienced in so constructing the same that the mating members, from which such a head is formed, can be firmly held together to satisfactorily form a support for the idlers.

The object of my present invention is, therefore, to produce a cutter head of the type described of such character as to obviate the difficulties heretofore experienced, several objects of the invention being more specifically pointed out in the description and claims.

The accompanying drawings illustrate an embodiment of my invention.

Figure 1 is a plan of the assembled cutter head, with no attempt to show the details of the chain; Fig. 2 a front elevation; Fig. 3 a section, on an enlarged scale, through the axis of one of the idlers; Fig. 4 a plan of the under member of the head; Fig. 5 a plan of the upper member of the head; Fig. 6 a section on an enlarged scale, on line 6-6 of Fig. 1 with the chain omitted, and Fig. 7 a fragmentary plan of the bottom of the chamber formed by flange 32.

In the drawings, 10 indicates the lower member and 11 the upper member which mate together to form the main body of the cutter head. The lower member is provided conveniently with a pair of rearwardly projecting fingers 12, 12 by means of which it may be fastened to the cutter head carriage of an ordinary mining machine. At each

forward corner of head member 10, I form a pocket 13 which is partially surrounded by a semi-circular rib 14, the two ribs 14 being connected at their ends by a rib 15. Ribs 14 and 15 are accurately machined at their upper edges so as to accurately and firmly mate with similar ribs 14' and 15' carried by head 11, the ribs 14' partially surrounding the pockets 13' formed at the opposite forward corners of the head member 11. In order to provide a further firm support for the middles of the upper and lower head members, I provide mating ribs 16 and 16', the upper edges of which are flush with the upper edges of the adjacent ribs, the arrangement being such that, by means of suitable clamping bolts 17, the two head members may be firmly clamped together with the edges of the two sets of ribs 14, 15 and 16 and 14', 15' and 16' firmly seated together.

Surrounding the forward edges of the two cutter head members are wearing plates or strips 18 which are detachably secured to the head members and are spaced apart a distance approximately equal to the thickness of the links of the cutter chain 19 of any well-known type, said wearing strips thus forming a channel between which the cutter chain runs and taking the wear thereof. These wearing strips may be readily replaced when worn so as to thus save the main body of the cutter head. Formed through head member 10 at the center of each pocket 13 is a bolt hole 21 through which is removably projected the bolt 22 which is threaded at its upper end and is of sufficient length to project into a shouldered opening 23 formed through plate 11 at the center of pocket 13'. A shouldered nut 24 is threaded upon bolt 22 and seated in pocket 23 so as to assist in clamping the upper and lower members 10 and 11 of the cutter head together. Sleeved upon bolt 22 is a hardened bushing 25 which, at its lower end, is provided with a plurality of equally spaced dowel pins 26 which fit within similarly arranged pockets 26' formed in plate 10 around the bolt head 21, the arrangement being such that the bushing 25 may be turned upon bolt 22 and held in any one of a series of positions in order to present a new wearing surface, as will be made to appear.

In practice, I find that the dowel pins 26 should be so placed that the bushing can be turned through an angle of about 90° and

reseated. Bushing 25 is preferably of a length equal to the distance between the inner faces of the two head members 10 and 11 and in order to hold the bushing in place, so that it may be firmly retained in place even after the removal of the upper head member from the lower head member, I form a pocket 25' in the upper end of the bushing, said pocket being so formed as to receive a clamping nut 27 threaded upon the upper end of bolt 22. The under face of member 11 carries a boss 100 which fits within the upper end of pocket 25' so as to form a firm support for the upper end of the bushing. Journaled upon bushing 25 is the hub of a sprocket wheel 28, the said hub having a length substantially equal to the length of the bushing. The sprocket wheel 28 should have its rim approximately midway between the upper and lower head members and, in order that proper provision may be made for the lubrication of this wheel, the rim is connected to the hub by a horizontal flange 31 which is of as great extent horizontally as possible, so that the line of junction between the outer portion of this horizontal flange and the depending rim may have extent enough to give sufficient strength to the wheel at this point. It has heretofore been common to produce an idler wheel of this general type but the custom has been to connect the depending rim with the upper end of the hub by an inclined portion, rather than a horizontal plate or flange, so that the line of junction between the depending rim and the hub was comparatively short, and, as the thickness of material cannot be great owing to the contracted space within which the wheel must rotate, wheels of that type universally break along the short line of junction between the rim and the hub. By making the wheel of the form shown in the drawings, where the depending rib is supported at the outer edge of the horizontal flange or plate, the line of junction is increased and the strength of the wheel at the point of junction with the depending flange is correspondingly increased.

Surrounding the hub of sprocket wheel 28 is an annular hub 32 which is preferably formed integral with the lower head member 10 and is of sufficient height to extend up into engagement, or practically into engagement, with the lower face of the horizontal flange 31 of the sprocket wheel 28. The internal diameter of rib 32 is somewhat larger than the diameter of the hub of wheel 28 so as to form an oil pocket 33 and the suitable packing 34 is mounted in an annular groove formed in the upper edge of rib 32 to engage the under face of flange 31 of the sprocket wheel and keep out the dust and grit. In order to properly lubricate bushings 25, the hub of wheel 28 is perforated, as indicated at 35. Oil may be introduced

into the oil chamber 33 through an oil passage 36 formed through flange 31 and an oil passage 37 formed through plate 11, the two oil passages being so arranged that passage 36 may be brought into registry with passage 37. Passage 31 is ordinarily closed by a screw plug 38.

In order to take the thrust applied to that portion of the chain lying between the two sprocket wheels, I provide a pair of wearing plates 41 which are detachably secured to the forward faces of ribs 15 and 15'. These wearing plates 41 are made of hardened material capable of withstanding considerable wear and are of a width equal to the height of the ribs 15 and 15' so that when the two mating members of the head are clamped together, the adjacent edges of the wearing strips 41 will be brought firmly together. If these adjacent edges of the wearing strips are brought firmly together throughout their width, the rubbing action of the chain would upset the corners of the wearing strips and tend to gradually pry the mating members of the head apart. In order, therefore, to avoid this difficulty, I undercut the adjacent corners of the two wearing strips as indicated at 42 so that space is provided for any such upsetting without possibility of interfering with the proper mating of the two head members.

As shown in Fig. 6, the beveled portions 42 will be at a sufficient angle to make it impossible for the coal dust to lie, with any stability, within the crotch thus formed.

In operation, the two mating members of the cutter head are, because of the extent and accurate mating of the ribs 14, 15 and 14', 15' firmly maintained together. As the cutter head is crowded forwardly into the coal breast, and the chain is driven in the direction indicated by the arrow in Fig. 1, practically all of the wear upon the lefthand bushing 25 will be upon its forward lefthand quadrant and practically all of the wear on the righthand bushing will be upon its forward quadrant. In the course of time, therefore, these limited portions of the bushings become so worn as to render the operation of the apparatus difficult; whereupon the operator may, by removing the upper head member 10, and by loosening nuts 27, raise the bushing 25 enough to free pins 26 from their pockets and turn the bushing 90°, whereupon a new wearing surface of the bearing, concentric with the bearing in the sprocket wheel, will be presented in working position. The sprocket wheel is preferably provided with a readily renewable bushing or lining 28', which, when renewed, will closely fit the newly presented wearing portion of bushing 25.

I claim as my invention:

1. In a cutter head, the combination of a pair of mating body members forming a

- wheel pocket therebetween, a clamping bolt extending through said body members in the axis of the pocket, a bushing sleeved upon said bolt between the body members and angularly adjustable thereon, a nut mounted upon said clamping bolt for independently clamping the bushing in place, and a chain wheel journaled upon said bushing.
2. In a cutter head, the combination of a pair of mating body members forming a wheel pocket therebetween, a clamping bolt extending through said body members in the axis of the pocket, a bushing sleeved upon said bolt between the body members and angularly adjustable thereon, said bushing having a pocket in its upper end, a nut mounted upon said clamping bolt for independently clamping the bushing in place, a boss carried by the upper body member and fitting within the upper end of said pocket, and a chain wheel journaled upon said bushing.
3. In a cutter head, the combination of a pair of mating body members forming a wheel pocket therebetween, a clamping bolt extending through said body members in the axis of the pocket, a bushing sleeved upon said bolt between the body members and angularly adjustable thereon, a nut mounted upon said clamping bolt for independently clamping the bushing in place, and a chain wheel journaled upon said bushing, said chain wheel comprising a central hub, a horizontally extending flange at one end of said hub and a depending rim at the outer edge of said horizontal flange, an annular flange carried by the lower head member and surrounding the wheel hub to form an oil pocket therefor.
4. A cutter head comprising a pair of mating body members having engaging portions to determine the spacing thereof, means for clamping the two members together, a chain wheel mounted between the two body members, a bearing bushing for said wheel arranged between the two body members, a clamping bolt passing through the two body members and through said bushing, a nut on said bolt for independently clamping the bushing upon one of the body members, a second nut on said bolt for clamping the other of said body members upon the bushing, and a flange carried by the lower body member and surrounding the hub of the chain wheel and spaced therefrom to form an oil well, the upper body member and the chain wheel having registrable perforations through which oil may be introduced into said oil well.
5. In a cutter head, the combination of a pair of mating body members forming a wheel pocket therebetween, a clamping bolt extending through said body members in the axis of the pocket, a shouldered nut on said bolt, said nut being countersunk in the surface of one of the body members, a boss carried by said countersunk body member opposite the countersinking, a bushing sleeved upon said bolt between the body members and angularly adjustable thereon, said bushing in its upper end having a pocket in the upper end of which fits the boss on said body member, and a chain wheel journaled upon said bushing.
6. In a cutter head, the combination of a pair of mating body members forming a wheel pocket therebetween, a clamping bolt extending through said body member in the axis of the pocket, a bushing sleeved upon said bolt between the body members and angularly adjustable thereon to any one of a series of positions, said bushing having a pocket in its upper end, a nut on said clamping bolt within said pocket, a boss carried by the upper body member and fitting within the upper end of said pocket, and a chain wheel journaled on said bushing.
7. In a cutter head, the combination of a pair of mating body members forming a wheel pocket therebetween, a clamping bolt extending through said body members in the axis of said pocket, and a bushing surrounding said bolt between said body members, said bushing being angularly adjustable to any one of a series of positions only when the body members are separated, and being provided at one end with a pocket, a nut threaded on the bolt and lying in the pocket to engage the bushing, and a body member being provided on its inner surface with a boss which projects into said pocket and being countersunk on its outer surface to receive the nut of said clamping bolt.
- In witness whereof, I, have hereunto set my hand and seal at Indianapolis, Indiana, this eighth day of August, A. D. one thousand nine hundred and eleven.

FRANK CARTLIDGE. [L. s.]
